CLAIM

The ornamental design for a portion of a display screen with indicator icons, as shown and described.

DESCRIPTION

The FIGURE is a front view of a portion of a display screen with indicator icons shown in the environment of a pulse oximetry monitor, where the circular indicator is about three quarters full and the triangular indicator is about a quarter full.

The broken line showings of the portion of the display screen and various regions thereof are included for the purpose of illustrating unclaimed portions of the portion of a display screen with indicator icons and form no part of the claimed design.
